REFRIGERATING APPARATUS

Raymond H. Bartels, New Orleans, La., assignor
to General Motors Corporation, Dayton, Ohio, a
corporation of Delaware

Application October 14, 1937, Serial No. 168,956

2 Claims. (Cl. 62—108.5)

This invention relates to freezing apparatus such as ice trays and particularly grid structures therefor employed in mechanically refrigerated household refrigerators.

Recently there has been placed on the market freezing devices for use in household refrigerators which devices include a tray having a removable unitary metallic grid structure disposed therein and comprising walls that are movable relative to other walls thereof for releasing ice blocks from the structure. In these grid constructions there is usually an operating element extended along the grid for engaging and moving the movable grid walls. In some grid constructions this operating element is of a particular cross-sectional contour to receive portions of the metal grid walls and the contour of the operating element, its association with the grid walls and its mounting upon the grid to provide a unitary construction is such that portions of the unitary structure are rendered inaccessible for cleaning. For example the assembly of the grid wall operating element upon a grid structure usually forms pockets or concealed surfaces that cannot be properly cleansed or sterilized due to the inaccessibility thereof for cleaning purposes. Therefore such structures have not been entirely satisfactory because they become unsanitary after a short period of use due to particles of fruits, jelloes, etc., being lodged in the pockets or inaccessible crevices of the grid structures. My invention contemplates the provision of means whereby such grid structures can be thoroughly cleansed and sterilized to thereby improve the conditions of use thereof.

An object of my invention is to provide an improved unitary metallic grid structure for disposition in an ice tray.

Another object of my invention is to provide means whereby a normally unitary grid structure or assembly having certain walls movable relative to certain other walls thereof by an operating element engaging the walls can have parts thereof moved away from other parts to thereby render concealed crevices or pockets of the structure accessible for cleaning purposes.

A further object of my invention is to provide means on a normally unitary grid construction whereby the grid structure can be disassembled to open up inaccessible pockets or crevices and to permit various walls or parts of the structure to be individually cleaned and sterilized for preventing contamination of the grid structure by particles of substances which become lodged in the pockets or crevices during use of the grid.

A still further object of my invention is to pro-

vide a normally unitary grid structure with a means which is simple in construction and operation to permit quick disassembly and reassembly thereof by the user in carrying out the foregoing objects of the invention in the maintenance of a sanitary grid structure. 5

Further objects and advantages of the present invention will be apparent from the following description, reference being had to the accompanying drawings, wherein a preferred form of the 10 present invention is clearly shown.

In the drawings:

Fig. 1 is a top plan view of an ice tray having a normally unitary grid structure positioned therein and in which grid structure my invention 15 is incorporated;

Fig. 2 is a side view of the apparatus disclosed in Fig. 1 showing ice blocks within the tray and grid;

Fig. 3 is a view of the grid structure removed 20 from the tray and showing the position of walls and other parts of the grid after having been moved to release ice blocks therefrom;

Fig. 4 is a view illustrating certain parts of the normally unitary grid assembly moved away from 25 other parts thereof to permit removal of the transverse grid walls from the longitudinal grid wall;

Fig. 5 is a view showing the longitudinal wall of the grid after having the transverse walls thereof 30 removed therefrom;

Fig. 6 is a view disclosing the contour of one of the plurality of transverse grid walls; and

Fig. 7 is a sectional view showing the construction in the present disclosure which permits dis- 35 assembly of the normally unitary grid structure.

In order to illustrate the present invention I have shown in Figs. 1 and 2 of the drawings a metal ice tray 10 having a normally unitary metallic grid structure 11 disposed therein. The 40 grid structure 11 includes a longitudinal wall 12 and a plurality of transverse walls 14 for dividing the interior of the tray into rows of open-top ice block cells or compartments 15. The longitudinal wall 12 of grid structure 11 has a plurality 45 of spaced apart slots or openings 16 cut therein and extending from the top edge thereof downwardly to a point near the central portion thereof. These slots 16 are adapted to removably receive a web portion 17 (see Fig. 6) of the transverse grid walls 14 which transverse walls have a slot 18 cut therein for straddling the web portion 19 (see Fig. 5) disposed below the slots 16 of the longitudinal grid wall 12. The transverse walls 14 are in this manner interlocked upon and re- 50 55

movably carried by the longitudinal wall 12 of the grid structure 11. It is to be noted that the slots 16 are considerably wider than the thickness of the transverse walls 14 for a purpose to be presently described. A substantially U-shaped in cross-section bar or rod 21 straddles the top of longitudinal grid wall 12 and has slots 22 therein adapted to receive and engage the uppermost part of the transverse grid walls 14 for locking these walls to the longitudinal wall 12. The bar or rod 21 is secured to the longitudinal wall 12 of the structure 11 by pins or the like 23 which pass through an elongated slot 24 provided adjacent each end of the longitudinal grid wall 12. The elongated slots 24 permit lengthwise movement of pins 23 and consequently rod or bar 21 relative to the longitudinal grid wall 12 to cause the walls of slots 22 in bar 21 to engage and tilt or move the transverse grid walls 14 relative to the longitudinal wall 12 to thereby remove ice blocks from the ice compartments 15 of the grid structure as shown in Fig. 3 of the drawings. Movement of bar 21 may be accomplished in any desired manner and I have shown a lever 26 pivotally mounted to the grid structure by a pin 27. The lever 26 is also connected by a pin 28, and through toggle link members 29 secured to one end of the longitudinal wall 12 by one of the pins 23, to rod 21.

In the present disclosure an upward movement of lever 26 causes its end 32 to apply force to the tray 10 to thereby elevate the grid structure 11 together with ice blocks adhering thereto relative to the tray. Further upward movement of lever 26 about its pivotal mounting 27, after the grid and ice have been removed from tray 10, moves the link members 29 about the pin 27 and thereby pulls on the rod 21 through the connecting pin 28 disposed at the lever end of the structure. Movement of rod 21 applies force to the top portions of the transverse grid walls 14 to tilt or move these walls relative to the longitudinal wall 12 to thereby enlarge the ice block compartments 15 and liberate ice blocks therefrom. The various walls of the structure and the slots provided therein are preferably arranged to cause the transverse grid walls to be moved relative to the longitudinal grid wall progressively from one end of the structure to the other end thereof to thereby reduce to a minimum the force required to break and release ice blocks from the grid 11.

It is to be noted that the assembly of the unitary grid structure shown forms a plurality of pockets, surfaces or crevices which are inaccessible for cleaning and these portions become contaminated by particles of fruits, jelloes or the like being lodged therein during use of the grid structure. Ordinarily the various parts of a unitary grid structure of the type disclosed cannot be disassembled or moved away from one another a sufficient distance to permit access to the concealed surfaces thereof and the particles of substance which become lodged in the pockets or crevices cannot be readily removed. It is the purpose of the present invention to provide means whereby various parts of the normally unitary grid structure 11 can be disassembled or moved away from one another to afford access to the concealed surfaces, pockets or crevices thereof to permit thorough cleaning of the structure. Therefore I have cut an opening 35 in the upper wall of the elongated slot 24 located at the end of the structure 11 opposite the lever end thereof. It is to be noted that the opening 35 is cut in the wall of slot 24 at the

center of the slot so that this opening will not interfere with the normal horizontal sliding movement of pin 23 therein from one end to the other end thereof. The opening 35 and the material surrounding or forming walls thereof provides means whereby the unitary metallic grid structure or assembly 11 can be partially disassembled or parts thereof moved a substantial distance away from other associated parts thereof. In Fig. 5 of the drawings I have shown one end of the U-shaped bar or rod 21 of the structure 11 released from the longitudinal grid wall 12 and elevated a substantial distance away from the grid walls 12 and 14 to permit ready access to the inside surfaces or pockets of bar 21 or rod 21 to thus permit cleaning of these surfaces. The elevation of bar or rod 21 relative to the grid walls as shown in Fig. 5 is accomplished by moving the lever 26 half way only of its total movement. The movement of lever 26 half way of its total movement causes the pin 23 to register or align with the opening 35 provided in slot 24 at the end of the structure 11 opposite the lever end thereof. After the pin 23 has been brought into vertical alignment with opening 35 in slot 24 the bar or rod 21 is grasped by the hand of the operator and elevated to cause removal of pin 23 from slot 24 through the opening 35 to thus release the one end of the grid wall locking means or rod 21 from the grid structure and to permit opening of the pockets formed by the association of the U-shaped rod 21 with the walls 12 and 14 to thereby permit access to and cleaning of the normally concealed surfaces of the structure 11. The loose mounting of the transverse grid walls 14 upon the longitudinal grid wall 12 permits sliding same upwardly therefrom while the locking bar 21 is in an elevated position. Removal of the transverse grid walls 14 from the longitudinal wall 12 permits further access to the slots and crevices in these walls for thorough cleaning of the grid walls. I have shown in Fig. 5 of the drawings the grid transverse walls 14 removed from the longitudinal grid wall 12 to permit thorough cleaning of the longitudinal grid wall. The separation of the transverse grid walls 14 from the longitudinal grid wall 12 permits cleaning of the individual plates or walls 14, one of which is shown in Fig. 6 of the drawings, independently of other walls of the structure 11.

While I have shown a preferred means of permitting disassembly or movement of certain parts of the normally unitary grid structure away from other parts thereof for the purpose of permitting thorough cleaning of these parts it is to be understood that other ways of carrying out the objects may be adopted without departing from the spirit of my invention. For example instead of cutting the opening 35 in slot 24 to provide for the removal of pin 23 from the slot and elevation of rod or bar 21 relative to the walls 12 and 14 of the grid, I may desire to substitute a screw or bolt for the pin 23 in which case the screw or bolt would be threaded into at least one leg of the U-shaped bar 21 for removal therefrom to cause separation of the one end of the bar 21 from the grid walls to carry out the objects of my invention.

It will be seen from the foregoing that I have provided an improved grid structure for disposition in an ice tray and which grid structure is normally unitary in construction and yet capable of being quickly disassembled for the purposes

herein specified without in any way affecting the operation of the unitary construction to cause movement of certain of its substantially rigid metallic walls relative to other walls thereof for releasing ice blocks therefrom. The disassembling of various parts of the normally unitary grid structure opens up or renders concealed pockets, surfaces or crevices formed by the cooperative association of the parts with one another accessible for cleaning to thereby prevent the grid structure from becoming contaminated by particles of fruits or the like frozen in the grid and tray at different intervals. My improvement permits the walls of the grid structure to be cleaned in the form of flat continuous plates to thereby eliminate the troublesome cleaning operation of intersecting portions of the walls or concealed surfaces of other parts of the grid structure. My invention is simple and inexpensive to provide and has been found through use of unitary grid structures of the general type disclosed to be a necessity in preventing contamination of substances to be frozen and for eliminating replacement of such structures after they have been in use a short period of time.

While the form of embodiment of the invention as herein disclosed, constitutes a preferred form, it is to be understood that other forms might be adopted, all coming within the scope of the claims which follow.

What is claimed is as follows:

1. A grid adapted to be disposed in a freezing tray comprising, a longitudinal partition and a plurality of separate transverse partitions carried thereby to form rows of ice block compartments, a member attached to said longitudinal

partition for locking said transverse partitions thereto, the attachment of said member to said longitudinal partition permitting movement of said member in one direction to move at least one of said partitions relative to others thereof for liberating ice blocks from said compartments, and the attachment of said member to said longitudinal partition also permitting movement of said member in another direction other than said one direction of movement thereof to unlock said transverse partitions and permit separation thereof from said longitudinal partition.

2. A grid adapted to be disposed in a freezing tray comprising, a longitudinal partition and a plurality of separate transverse partitions carried thereby to form rows of ice block compartments, a member attached to and extending along said longitudinal partition for locking said transverse partitions thereto, the attachment of said member to said longitudinal partition including an elongated opening provided in said longitudinal partition and a pin extending through the opening and secured to said member, the opening permitting movement of said member to move the transverse partitions relative to said longitudinal partition for liberating ice blocks from said compartments, and said longitudinal partition having a slot extending from a peripheral edge thereof to said opening for permitting movement of said pin out of said opening for unlocking said member from said longitudinal partition whereby said transverse partitions may be detached from the longitudinal partition.
